SPOOLER.

1,152,845.

Specification of Letters Patent.

Patented Sept. 7, 1915.

Application filed February 14, 1913. Serial No. 748,280.

To all whom it may concern:

Be it known that I, ALONZO E. RHOADES, a citizen of the United States, and resident of Hopedale, county of Worcester, State of Massachusetts, have invented an Improvement in Spoolers, of which the following description, in connection with the accompanying drawing, is a specification, like characters on the drawing representing like parts.

This invention relates to spoolers, and especially to spoolers of that type wherein the bobbin from which the yarn is drawn is supported on a spindle instead of being supported in a pan.

In the operation of spoolers, the spool on which the yarn is wound is rotated at a substantially uniform rate of speed, and therefore the yarn is drawn from the bobbin at a substantial uniform surface speed. Where the bobbin from which the yarn is being spooled is wound with what is known as a "warp wind", that is, a wind in which each layer of yarn extends the full length 25 of the bobbin, the pull or tension on the yarn due to drawing the yarn from the bobbin is very nearly uniform, and does not change appreciably from one layer to the other of the yarn mass on the bobbin. But where the bobbin is wound with the so-called "weft wind" the tension on the yarn varies considerably from one end of each layer to the other. This is due to the cone shape of each layer and to the fact that as one end of each 35 layer has a smaller diameter than the other end of the layer the uniform surface speed at which the yarn is delivered to the spool will cause the bobbin to have a variable speed of rotation, the bobbin rotating faster when the yarn is being unwound from the small end of the layer than when the yarn is being unwound from the large end of the layer. This varying speed of rotation of the bobbin produces a varying tension or 45 pull on the yarn, the tension being greater when the yarn is being unwound from the portion of smaller diameter than when the yarn is being unwound from the portion of larger diameter. Moreover, the inertia of the bobbin is likely to cause it to overrun as the yarn being delivered passes from the small to the large end of the layer. If the bobbin does overrun a kink is very likely to form in the slack of the yarn produced by 55 the overrunning, and when the yarn is drawn taut again the sudden tension im-

parted thereto is very likely to cause the yarn to break. This is especially true with fine counts of yarn, and when the yarn mass on the bobbin is comparatively large.

In my present invention I aim to provide a novel tension device for the bobbin which is adapted to compensate for the tension or pull on the yarn caused by the variation in the drag of the bobbin, and which applies 60 a retarding friction to the bobbin as the latter tends to overrun, thereby checking such overrunning tendency.

By means of my invention I find that 70 yarn of the most tender and delicate character can be readily spooled from bobbins with a minimum breakage.

The various novel features of my invention will be fully described in the subjoined specification and particularly pointed out in 75 the following claims.

Figure 1 is a transverse sectional view of a sufficient portion of a spooler with one embodiment of my present invention embodied therein; Fig. 2 is an enlarged side 80 elevation of a bobbin-holder embodying my invention, the bobbin being indicated by dotted lines; Fig. 3 is an outer end view of the bobbin-holder, viewed axially of the bobbin-receiving spindle; Fig. 4 is a dia- 85 gram view showing the operation of my improved tension member.

Referring to Fig. 1, the main frame A' drum-shaft A* for driving the rotatable spool-carriers S on which are mounted the 90 spools A' to receive the thread or yarn from the bobbins, the horizontal rod B (one at each side of the frame) on which the bobbin-holders are mounted, the thread-guides t, the reciprocating traverse-rods, as T, on 95 which they are mounted, the boxes E for the full bobbins, and the open-topped hoppers H for the spent bobbins, may be and are of well known construction and substantially as shown in my prior Patent No. 744,797 100 granted November 24, 1903.

While only a portion of one side of the spooler is shown in Fig. 1 it will be understood that each side of the main frame carries a series of rotatable spool-carriers, and that each series of spool-carriers has a corresponding set of thread-guides, as t, and a series of bobbin-holders is mounted on the rod B at each side of the frame.

The bobbin-holder embodying my present 110 invention comprises a casting having a jaw 1 to embrace the rod B, an elongated arm 2

rigidly connected with and laterally offset from the jaw by the ear or bend 3, and a depending, preferably internally-threaded hub 4 into which is screwed the tubular shank 5 of a bearing 6, the hub being formed at the bottom of the jaw, as herein shown. The bearing supports a freely rotatable bobbin-receiving spindle 7, the pintle 8 thereof entering the bearing, and an annular collar 9 on the spindle serves as a stop for the butt of the bobbin. The bearing has an oil reservoir 10 the lid of which is prolonged at 11 to overhang the collar and retain the spindle in place in the bearing.

As shown in Fig. 3 the hub 4 has a set-screw 12 to engage the bearing 6 and prevent any tendency of the latter to turn in the hub. In practice the usual spinning-spindle of the bolster-bearing type, and its bearing base, may be used, as will be observed from an inspection of Fig. 2, the base or bearing 6 being held in the hub 4 instead of in a spindle rail. The spindle 7 is substantially parallel to the arm 2, and is located below and at one side of it, as shown, thereby affording ample room for a bobbin carrying a yarn-mass of large diameter. The jaw 1 partly embraces the rod B and is clamped fixedly thereon by a suitable set-screw 13, the spindle 7 being set at the requisite upward and frontward inclination to properly deliver the yarn. The arm 2 is apertured at 14, Fig. 2, and the apertures are provided with alined holes 15 to receive loosely the oppositely turned ends 16 of a tension member, preferably made of heavy wire and having a straight, elongated portion 17 connected by the bends 18, 19 with the ends 16, so that the tension member is pivotally supported by the arm 2 with the straight portion 17 adjacent and parallel to the spindle 7.

As shown in Fig. 3 the straight parts of the bends 18, 19 adjacent the ends 16 are long enough to extend from the arm 2 above and across the spindle, and when the latter is bare the bottoms of the apertures 14 serve as stops for the bends, to limit downward swing of the tension member. The bend 19 is flared at its front end, at 20, to permit the ready application of the bobbin 21 to the spindle 7, the butt of the bobbin resting against the stop-collar 9 and the bobbin frictionally engaging the spindle to rotate therewith. The yarn is led under the straight, elongated part 17 of the pivoted tension member and thence up to the reciprocating thread-guide 4, as usual. The tension member is constructed so that normally a portion thereof will engage either the bobbin or the yarn mass thereon, thereby to apply to the bobbin a frictional pressure. Said tension member may, therefore, be called a combined tension and braking member.

In the illustrated embodiment of the invention the portion of the tension member which has frictional engagement with the bobbin or the yarn mass is the portion designated 22, although it would be within my invention to so shape this tension member that some other portion thereof would normally have frictional engagement with the bobbin or yarn mass, with the bobbin support or with any part connected to and rotating with the bobbin, and the term bobbin is to be understood in the claims as including either. In the operation of the device when the parts are at rest the portion 22 of the tension device rests on the bobbin or on the yarn mass, according to the amount of yarn which the bobbin may have thereon.

The direction in which the yarn is drawn off from the bobbin is such relative to the plane of the portion 17 of the tension member and the pivots 16 that frictional engagement of the yarn with the part 17 will tend to swing the tension member upwardly or away from the bobbin more or less, depending upon the amount of tension on the yarn, and when the tension on the yarn is sufficient the portion 22 of the tension member will be raised or moved from contact with the bobbin or yarn mass. When the tension on the yarn diminishes sufficiently, the portion 22 of the tension member will then be lowered or move into contact with the bobbin or yarn mass. As the yarn is drawn off from the bobbin the speed of rotation of the bobbin varies according to the diameter of the yarn mass thereon, thus varying the tension to which the yarn is subjected and causing a vibrating movement of the tension member 17. This variation is quite marked as the yarn unwinds back and forth between the minimum and maximum diameters of the yarn mass of the ordinary weft or filling wind. The vibrating movement of the tension member compensates for this variation in the speed of the bobbin. If at any time the bobbin tends to overrun, then the slack which is thus put into the yarn will allow the tension member to drop into engagement with either the bobbin or yarn mass thereon, and thus a braking pressure or retarding friction will be applied to the bobbin which will check the overrunning tendency. My improved tension member thus operates automatically to maintain a substantially uniform tension on the yarn, to compensate for the variation in tension arising from the variation in speed of the bobbin rotation due to varying diameter of yarn mass, and to prevent breakage due to overrunning.

Having fully described my invention, what I claim as new and desire to secure by Letters Patent is:

1. In a spooler, a bobbin-holder comprising

ing a clamping jaw having a depending hub and an elongated, laterally offset-arm, a bearing fixed in the hub, a bobbin-receiving spindle mounted to rotate freely in the bearing and extended substantially parallel to and below the arm, and an elongated tension member pivotally connected with the arm and having a portion extended lengthwise of the spindle at the side thereof farthest from the arm, the tension member engaging frictionally the rotating yarn mass on the bobbin.

2. In a spooler, a bobbin-holder comprising an elongated arm provided at its inner end with a laterally offset, axially parallel bearing, a bobbin-receiving spindle mounted to rotate freely in the bearing, and a tension member having an elongated portion extended lengthwise of and adjacent the spindle and connected pivotally by bends with the arm, the connecting bends extending over the spindle to enable said member to rest upon and engage frictionally the yarn mass.

3. In a spooler, a bobbin holder comprising a bracket having a laterally offset ear and a rigidly connected, elongated arm, a bearing fixedly connected with the bracket below the ear, a bobbin-receiving spindle freely rotatable in the bearing and extended parallel to and beyond the arm, a tension member pivotally connected with the arm and having an elongated portion located adjacent the spindle at the side thereof farthest from the arm, and means on the arm to limit downward swinging movement of the tension member.

4. In a spooler provided with a rotatable spool-carrier and a reciprocating thread-guide, and a horizontal rod fixedly mounted below the spool-carrier, in combination, an upwardly inclined and prolonged arm fixedly mounted at its inner end on the rod, a bearing offset laterally from and fixedly connected with the arm below it, a bobbin-receiving spindle freely rotatable in the bearing and in substantial parallelism with the arm, and a tension member pivotally connected with the arm and having an elongated portion adjacent and extended lengthwise of the spindle the yarn passing under said elongated portion as it travels from the bobbin to the spool, said tension member preventing overrunning of the bobbin and exerting the requisite tension on the yarn.

5. In a spooler provided with a rotatable spool-carrier and reciprocating thread-guide, in combination, a freely rotatable spindle, a bobbin mounted on said spindle with yarn wound thereon with a weft or filling wind, and means for automatically controlling the rotation of the bobbin to deliver the yarn

therefrom at a substantially uniform tension.

6. In a spooler provided with a rotatable spool-carrier and reciprocating thread-guide, in combination, a freely rotatable spindle, a bobbin mounted on said spindle with yarn wound thereon varying longitudinally of the bobbin in its mass diameter, and means for automatically applying friction to the bobbin to compensate for the variation in its speed of rotation as the yarn is unwound therefrom to the spool.

7. In a spooler provided with a rotatable spool-carrier and reciprocating thread-guide, in combination, a freely rotatable spindle, a bobbin mounted on said spindle with yarn wound thereon varying longitudinally of the bobbin in its mass diameter, and a tension member mounted to swing by gravity into contact with the bobbin and engaging the run of yarn from the bobbin to the thread-guide, whereby the variation in tension on the yarn, due to a variation in speed of rotation of the bobbin while the yarn is unwound therefrom, causes the tension member to swing into or out of contact with the bobbin and restore the normal tension.

8. In a spooler provided with a rotatable spool-carrier and reciprocating thread-guide, in combination, a freely rotatable spindle, a bobbin mounted on said spindle with yarn wound thereon varying longitudinally of the bobbin in its mass diameter, and a tension member movable into contact with the bobbin and engaging the run of yarn from the bobbin to the thread-guide whereby the variation in tension on the yarn, due to a variation in speed of rotation of the bobbin while the yarn is unwound therefrom, causes the tension member to move into or out of contact with the bobbin and restore the normal tension.

9. In a spooler provided with a rotatable spool-carrier and a reciprocating thread-guide, in combination, a freely rotatable spindle on which the bobbin is mounted, a support for the spindle, a pivotally mounted combined tension and braking member having a portion to engage the yarn and apply a varying tension thereto, depending on the tension given to the yarn from the rotating bobbin, and another portion to frictionally engage the bobbin or the yarn mass thereon when the bobbin overruns.

In testimony whereof, I have signed my name to this specification, in the presence of two subscribing witnesses.

ALONZO E. RHOADES.
